[57] CLAIM

The ornamental design for a combined screen printing ink squeegee and screen tensioning holder, as shown and described.

DESCRIPTION

FIG. 1 is a perspective view of a first embodiment of a

combined screen printing ink squeegee and screen tensioning holder showing our new design with laterally spaced skids;

FIG. 2 is a top plan view of the combined screen printing ink squeegee and screen tensioning holder shown in FIG. 1;

FIG. 3 is a left side elevational view of the combined screen printing ink squeegee and screen tensioning holder shown in FIG. 1, the right side elevational view being a mirror image thereof;

FIG. 4 is a front elevational view of the combined screen printing ink squeegee and screen tensioning holder shown in FIG. 1;

FIG. 5 is a perspective view of a second embodiment of a combined screen printing ink squeegee and screen tensioning holder showing our new design with laterally spaced rollers;

FIG. 6 is a top plan view of the combined screen printing ink squeegee and screen tensioning holder shown in FIG. 5;

FIG. 7 is a left side elevational view of the combined screen printing ink squeegee and screen tensioning holder shown in FIG. 5, the right side elevational view being a mirror image thereof; and,

FIG. 8 is a front elevational view of the combined screen printing ink squeegee and screen tensioning holder shown in FIG. 5.

The portions of the bottom and rear views of both embodiments of the combined screen printing ink squeegee and screen tensioning holder, not shown, form no part of the claimed design.
